Leopold Demuth Inventor
By his Attorney Frank H. Hart

UNITED STATES PATENT OFFICE.

LEOPOLD DEMUTH, OF NEW YORK, N. Y.

TOBACCO PIPE.

Application filed May 17, 1923. Serial No. 639,550.

To all whom it may concern:-

Be it known that I, LEOPOLD DEMUTH, a citizen of the United States, residing at New York, in the county of New York and State of New York, have invented certain new and useful Improvements in Tobacco Pipes, of which the following is a specification.

This invention relates generally to tobacco pipes, and more particularly to an improved construction of mouthpiece to be used in connection with pipes in which the bit is made detachable from the bowl by means of a "push" that enters the stump of the bowl to connect the two parts of the pipe rigidly together. In order to prevent breakage such as frequently results from the tapping or knocking of the pipe against a hard surface to dislodge ash and other residue from the bowl, it has been common practice to make the "push" of a material like aluminum for instance, which may be molded in the end of the bit or mouthpiece, thereby strengthening the bit at its connection with the stump of the bowl. While the bit thus provided with a molded-in "push" or connection is undoubtedly stronger than a mouthpiece made throughout of hard rubber for instance, with an integral reduced end or tenon, it is sometimes found in practice that while the aluminum "push" or tenon fits very well when the pipe is new, the fit is apt to become loose when the wood shrinks after a period of use. So far as the fit between tenon and bowl is concerned, the hard rubber bit with integral tenon gives very satisfactory results, because the hard rubber appears to have more resilience and possibly expands slightly as the wood into which it is inserted shrinks.

It is an object of my invention accordingly to provide a construction of bit or mouthpiece which will yield the advantages of a reinforcement at the point of connection, without losing the advantage as to continued tightness of fit that goes with a well-made hard rubber tenon. And I aim incidentally to accomplish this object by an arrangement which gives a very distinctive and attractive finish to the article.

Other objects and aims of the invention, more or less broad than those stated above, together with the advantages inherent, will be in part obvious and in part specifically

referred to in the course of the following description of the elements, combinations, arrangements of parts, and applications of principles constituting the invention; and the scope of protection contemplated will appear from the claims.

In the accompanying drawing, which is to be taken as part of this specification, and in which I have shown merely a preferred form of embodiment of invention,

Figure 1 is a sectional view through a tobacco pipe embodying my invention;

Figure 2 is an elevation of the bit disconnected from the bowl; and

Figure 3 is an elevation of the "push" or connection piece before the same has been molded into the mouthpiece proper.

Referring to the numerals on the drawings, there is shown at 4 a bowl, which may be of wood or other suitable material, having a stump 5, into which is inserted the connection or tenon of the mouthpiece or bit 6. The mouthpiece 6 may be of hard rubber or other suitable material which is capable of being molded around a connection piece 7. As suggested above, I prefer that the connection piece 7 shall be of aluminum or some other metallic or other material which will have desirable qualities of strength, non-corrosiveness, etc. In order to effect a strong union between the hard rubber bit and the metallic connection, the connection piece, which is generally a tube, is provided on its exterior surface with a square thread 8, preferably of considerable pitch; this thread terminating short of what is the outer end of the tenon when the latter is combined with the bit. The bit is molded around the connection piece 7 and around the thread 8, as clearly appears from Figure 1, in such a way that there is a non-obstructed smoke passage 9 through the bit and the tenon or connection piece. The bit is provided with a shoulder 10 at its inner end which defines the "push" or tenon, and which determines the length of the projecting part of the piece 7. And the spiral groove defined by the thread 8 in the projecting part of the piece 7 is filled with the material of the bit, for instance, hard rubber, substantially up to the level of the thread, and so that there is in this groove an integral reduced extension of the bit

100
105

proper, spiral in form and with the thread 8 coming to the surface. As set forth above, the thread 8 ends at a point 11 short of the inner end of the piece 7, and the integral extension of the bit likewise extends no further than a plane perpendicular to the axis of the bit and which passes through the end 11 of the thread. Thus, there is provided a circumferential shoulder 12.

10 From the construction described it will be evident that there is provided a tenon having an exterior surface for frictional engagement with the walls of the stump, which surface is in part metallic and in part hard rubber. The connection between the mouthpiece and the bowl is reinforced to the extent that the piece 7 is stronger than the mouthpiece proper, and the connection piece is solidly anchored in the mouthpiece. The 15 tenon possesses the advantage that it is easily inserted into and removed from its seat, both by reason of the metallic surfaces which are exposed, and because of the screw action which is possible. At the same time, 20 because of the partial hard rubber surface of the tenon, continued tightness of fit is guaranteed. At the same time the advantages of aluminum (non-corrosiveness, cooling of the smoke, etc.) are retained.

30 It is evident that by regulating the pitch of the thread 8, or the width thereof, at least as to that part of the piece 7 which constitutes the connection, the relative proportions of metallic and hard rubber surfaces exposed in the tenon can be controlled, according to need. The article is found to give entire satisfaction in use from the utilitarian standpoint, and is entirely distinctive and attractive in appearance.

40 It is within the purview of the invention to make the connecting piece separable from the bit proper. In that case, the piece 7 will not be molded in with the mouthpiece, but the threads at one end thereof (the 45 right-hand end in Figure 3) will be screwed into the correspondingly threaded end of the bit, and of material, such as the hard rubber of the bit, will be molded in position between the spirals of the thread at the left-hand end of the piece, that is, the end which will constitute the "push" when the parts are assembled. With this arrangement the mouthpiece would perhaps be not so strongly reinforced, but there would be the advantage of replaceability of the connection piece if the fit between the tenon and the bowl should become loose.

50 It will be understood that while I have in this specification referred specifically to hard rubber, aluminum, and other materials, I intend no limitations whatever to particular materials. The essentials of the invention are in the provision of a reinforcing connection piece whose outer end constitutes 55 the tenon of the bit, and which outer end

is provided with certain portions which have greater frictional and or elastic qualities than other portions. In another aspect, the invention includes a bit of hard rubber or the like, with a reinforcing connection piece molded therein and constituting a tenon, this reinforcing piece being of stronger material than that of the bit itself and the tenon presenting distinct surfaces which are integral respectively with the material of the bit and the material of the connection piece.

70 Inasmuch as many changes could be made in the above construction, and many apparently widely different embodiments of my invention could be made without departing from the scope thereof, it is intended that all matter contained in the above description or shown in the accompanying drawings shall be interpreted as illustrated 75 and not in a limiting sense.

80 It is also to be understood that the language used in the following claims is intended to cover all the generic and specific features of the invention herein described 85 and all statements of the scope of the invention which, as a matter of language, might be said to fall therebetween.

I claim:

1. A bit having a tenon end comprising 95 an internal tubular reinforce made of material different from the material of the bit proper, and a friction member overlying the tubular reinforce, a portion of the outer wall of the reinforce extending through the 100 said friction member flush with the outer surface of the latter.

2. A bit having a tenon end comprising an internal tubular reinforce made of material different from the material of the bit proper, and a member integral and continuous with and of the same material as the bit proper, overlying the tubular reinforce, a portion of the outer wall of the reinforce extending through the said member 110 flush with the outer surface of the latter.

3. A bit having a tenon end comprising a reinforcing member extending from the bit and made of material different from that of the bit proper, and a friction member integral with the bit and overlying the reinforcing member, the reinforcing member and the friction member in their assembled relation having flush exterior wall portions. 115

4. The device described in claim 3 in which the connecting piece is of generally tubular form, with a plurality of portions projecting above the outer surface thereof, and in which there are portions integral 125 with the bit itself positioned upon the exterior of the connection piece and between said projecting portions of the connecting piece.

5. A device as described in claim 3 in 130

which the connecting piece is of tubular form with a square thread on the exterior thereof, a portion of the tube being embedded in the bit and another portion projecting beyond the end of the bit, and in which the spiral groove defined by the thread in the projecting part of the connecting member is filled to the level of the

thread with material integral with that of the bit.

In testimony whereof I affix my signature in presence of two witnesses.

LEOPOLD DEMUTH.
